UNITED STATES PATENT OFFICE.

JONATHAN F. ELLSWORTH, OF HYANNIS, NEBRASKA.

MOWER.

SPECIFICATION forming part of Letters Patent No. 681,446, dated August 27, 1901.

Application filed June 6, 1900. Serial No. 19,286. (No model.)

To all whom it may concern:

Be it known that I, JONATHAN F. ELLSWORTH, a citizen of the United States, residing at Hyannis, in the county of Grant and 5 State of Nebraska, have invented new and useful Improvements in Mowers, of which the following is a specification.

This invention relates to machines for cutting grass and weeds along the rails of a rail-way-track; and its object is to provide efficient means for the purpose.

The invention consists in the construction herein described and pointed out.

In the accompanying drawings, Figure 1 is 15 a perspective showing one-half the improved device applied to a hand-car, the latter being shown only in part. Fig. 2 is a partial front elevation. Fig. 3 is a plan. Fig. 4 is a partial side elevation. Figs. 5 and 6 are respectively a partial perspective and section 20 showing connections of a shoe, cutting-knife, and frame. Fig. 7 is a section of cutting-blades adjusted for sharpening one of them. Fig. 8 is an enlarged detail showing the pivotal connection of a pilot-wheel frame and runner-frame with a supporting-shaft. Fig. 25 9 is a view, on an enlarged scale, of a socket in a pilot-wheel frame to receive the foot of a mower-elevating screw.

Numeral 1 denotes the floor of a hand-car of ordinary construction, which may have the usual or any desired means of propulsion or may be pushed directly by hand or by a motor having its own supporting-wheels.

25 2 indicates an axle of the car.

The invention is conveniently applicable to so-called "hand-cars" such as now in use; but any carriage adapted to support the mechanism herein described and suitable to run 30 on the track-rails may be employed.

In the present instance two pieces of scantling A, having any suitable dimensions, are bolted or clamped to a hand-car, one on each side, as clearly shown in Fig. 1. Another 45 piece B is secured to the front end of the car and also secured by metal straps C to the side pieces. These pieces constitute a supporting-frame supplemental to the car platform or frame and provide for attaching the machine to different cars without seriously mutilating them. In Figs. 1, 3, and 4 only a

part of the supplemental frame is shown. Fig. 3 indicates that said frame has two side bars A, connected by a cross-bar B. Obviously the supplemental frame could be fixed to the 55 car by suitable removable clamps.

33 denotes hangers fixed to the cross-piece B, there being two hangers on each side.

5 denotes a shaft turning in bearings 4 in the lower end of the inner hangers.

5^x indicates rods each having its inner end screwed either into an inner hanger 3 or into a suitably-threaded piece or plate fixed to such hanger, and thereby held from rotating. The outer ends of rods 5^x are shaped to receive a tool whereby they may be screwed into said plate or other inner support.

5^z denotes blocks loosely supported on rods 5^x.

6 indicates forked frames pivotally supported from the rods 5^x by the medium of blocks 5^z.

7 denotes members of the frame that extend forwardly and downwardly and are secured to shoes or runner 8 and to vertically-disposed frames 9 near their connection with said runners, as by a bolt 7^x. The frames 9 have each two uprights 9^x, and the members of the frame 6 are fastened to said uprights. Each vertical frame 9 has a top cross-bar 10. Said frame is stayed by the curved braces 11, and its top is rigidly connected to the frame 6 by bars 12.

13 denotes the handle of a screw connecting the frame 9 with the pilot-wheel frame 85 (to be described) and adapted to vertically adjust the cutters, runners, and their supporting-frames.

The cutter-supporting shaft 14 operatively supports two cutters adapted to cut each side 90 of the track-rail. They may be of usual or of any approved form. As represented, they are provided with curved blades 15 and are combined with a stationary blade 16, fixed between the runners 8 at or near their junction 95 with the uprights 9^x. The brackets supporting shaft 14 have elongated slots 14', so that said brackets can be moved to change the positions of the cutters relatively to the runners.

17 denote pilot-wheels, and 18 pilot-wheel frames connecting the axle-bearings of the pilot-wheels with the rods 5^x, upon which said

frames are pivoted by means of the block 5^z. Each frame 18 has a semicircular part 33^x situated under the cutter-shaft and such part in the present instance is stiffened by 5 short similarly-curved pieces 18'. The frame 18 also comprises a cross-bar 18'', curved and joined to the frame, as shown. The side members of frame 18 are also connected integrally by a cross-bar 18''', having a downwardly-bent 10 part 18''. The frames 6 and 18 are connected by pivots 18^x, (best shown in Fig. 8,) extending through said parts 6 and 18 and through flange 5^z, which depends from the bearing-block 5^z, supported on rod 5^x and capable of 15 turning thereon. By turning the handled screw-rod 13 through cross-bar 28 of frame 9 said frame can be adjusted relatively to the frame 18. The foot 33^y of said screw-rod may be spherical and connected to bar 33^{xx} by a 20 curved socket-piece 33^z, Fig. 9. The curved and lower portion of the frame 18 may be supplemented by a curved and corrugated steel piece 33^{xx}, (shown in Fig. 1,) and the foot of rod 13 can be stepped in the groove 34 (see 25 Fig. 9) in said piece or segments. As the rod 13 is screwed through the cutter-frame bar 28 the frame is pushed up and away from the stationary frame of the pilot-wheel.

The particular form of the frames and other 30 details may be varied without departing from the main features of the invention.

It will be understood that there are a pilot-wheel and two cutters for each rail and that each pair of cutters has its own frames and 35 shaft.

Each pair of cutters is driven by a sprocket-wheel 19, fixed on a shaft 14 and connected by a chain 20 to and driven by a sprocket-wheel 21 on the shaft 5. Said shaft has a 40 sprocket-wheel 22, connected by chain 23 with a sprocket-wheel 24 on the car-axle, all as shown, whereby when the car is driven or pushed forward the cutters are operated.

27 denotes a lever having a fulcrum at 28 45 and adapted to raise the cutter-frames, cutters, and runners to provide for passing over switches or other obstructions.

33 are segments supported on the supplementary frame adjacent the levers 27, and 34^x 50 are lever-holding pawls engaging the teeth of the segment-racks.

35 are posts on the supplementary frame to provide bearings for pulleys 36 for flexible connections 37 between the cutter-frames and 55 the levers.

If desired, the cutter-frames, cutters, and runners can be turned back to a position of rest on the car. The pilot-wheels 17 and their frames may also be turned back onto the car by 60 simply turning the frames about the rods 5^x.

In Figs. 5, 6, and 7 is shown a construction whereby the stationary knife 16 can be tilted and held in such relation to the curved blades 15 that the latter may be sharpened by rotating them against knife 16. Said knife may be supported so as to be capable of turning on pivots, such as 9'.

8' are screw-bolts securing the runners 8 to the frame.

8'' are screws securing blades 16 to the 70 shoes. The blades can be slightly tilted on their pivots 9', either forwardly or backwardly, by suitably loosening one of each pair of screws 8'' and tightening the other. If the front edge of the blade 16 be tilted up so that 75 the dulled edges of the rotary blades strike on the upper face of blade 16 near its edge, said rotary blades will be sharpened. By tilting up the rear edge of blade 16 and providing it with oil and emery the rotary blades 80 may be sharpened by running the mower-blades backwardly.

To insure smooth and steady action, rollers 30 are provided to rotate in supports 31, riveted to the inner members 7 of the forked 85 frame 6 near the foot of each, just above runners 8, said members constituting extensions of frame 9. Said rollers bear on the rail and tend to check lateral vibrations of the mechanism.

32 denote guards for the sprocket-wheels 19 and chains 20. The bars are curved to conform to the wheel in front and are fixed to the frame. They prevent grass or weeds from catching under the chain. Guards being on 95 opposite sides of a rail and fixed to and carried by a sickle-bar supporting reciprocating blades have been proposed, and such construction is not herein claimed. It is characteristic of the present improvement that 100 the guard is drawn along the rail, whereby it is less liable to be injured by an accidental obstruction and also that it is provided with a special support including an extension of a cutter-supporting frame below the shaft of 105 a rotary cutter.

Having thus described my invention, what I claim as new, and desire to secure by Letters Patent, is—

1. In combination with a car to run on a 110 track, a rotary cutter, a cutter-supporting frame, a runner supported by said cutter-supporting frame in position to travel on the ground beside a track-rail, a runner-guiding and cutter-frame-steadying roller to bear on a 115 track-rail, and a roller-support connected with the cutter-supporting frame, the roller-support being supported from the cutter-frame at a point in advance of the roller.

2. In combination with a car to run on a 120 track, a cutter, a cutter-supporting frame, a steady-roller to bear on a track-rail, an extension of the cutter-supporting frame situated in front of and below the cutter-shaft, and a support for said roller carried by said 125 extension, the roller being at the rear end of its support whereby it is drawn along the rail.

3. In combination with a car to run on a track, a cutter, a cutter-supporting frame, a runner, a steady-roller to bear on a track-rail, an extension of the cutter-supporting frame situated in front of and below the cutter-shaft, and a support for said roller carried by said extension, the roller being at the 130

rear end of its support whereby it is drawn along the rail, said extension being fixed to the runner.

4. In a machine adapted to run on a track, 5 a rotary cutter, a cutter-supporting frame, a pilot-wheel, a steadyng-roller to bear on the side of a track-rail, an extension of the cutter-supporting frame situated in front of and below the cutter-shaft and extending to the 10 front of the cutter, a support for said roller carried by said extension, and a runner, said extension being fixed to the runner and the roller being drawn along the rail.

5. In combination with a car to run on a track, a cutter, a cutter-supporting frame, and a steadyng device for said frame, said device being fixed to the said frame in front of the cutter and extended rearwardly of the point of its support on the frame, and adjacent 20 the side of a track-rail, whereby it is adapted to be drawn along in contact with said rail.

6. In combination with a car to run on a track, a mower-supporting frame, a pilot- 25 wheel frame carrying a pilot-wheel in position to run on one of the track-rails, said frames being pivotally supported by the car on a horizontal axis, and a screw screwing through a part of the mower-frame and bearing on the 30 pilot-wheel frame, whereby the mowers can be raised or lowered with respect to the pilot-wheel frame by turning said screw.

7. In combination with a car to run on a track, a mower-supporting frame, a pilot- 35 wheel frame carrying a pilot-wheel in position to run on one of the track-rails, said frames being pivotally supported by the car on a horizontal axis, and a screw screwing through a part of the mower-frame and bearing 40 on the pilot-wheel frame, whereby the mowers can be raised or lowered, said pilot-wheel frame having a supplemental piece situated behind the mower and provided with a socket or groove in which the screw is stepped.

45 8. In combination with a car to run on a

track, mower-supporting frames, hangers mediate fixed to the car, rods fixed in the hangers to pivotally support the mower-frames, and a rotating shaft to drive the mowers, said shaft being supported to turn in a part of 50 said hangers.

9. In combination with a car to run on a track, a detachable supplementary frame fixed to the car, brackets depending therefrom, rods in said brackets, a mower-supporting frame pivotally connected to said rods and thereby to the detachable frame, a segment, a lever adjacent the segment, a flexible mower-frame-raising connection attached to the lever, and a holding-pawl carried by said lever, said segment, lever and coöperating parts being also supported by the detachable frame. 55

10. In combination with a car to run on a track, a shaft held in brackets supported by the car, a pilot-wheel, a pilot-wheel frame pivotally supported by the car, a mower-supporting frame, mowers and runners supported by said mower-supporting frame, which frame is pivotally supported by the car, and means bearing on the pilot-wheel frame for elevating 70 the mower-supporting frame to lift the runners and mowers.

11. In combination with a car to run on a track, a shaft, brackets supported by the car for holding the shaft, a pilot-wheel, a pilot-wheel frame, a mower-supporting frame, mowers and runners carried by the mower-supporting frame, said frames being pivotally supported concentric to the shaft, a lever fulcrumed on the car for lifting the runners and 80 mowers simultaneously, and means bearing on the pilot-wheel frame and connected with the mower-supporting frame. 75

In testimony whereof I have hereunto set my hand in presence of two subscribing witnesses. 85
